UNITED STATES PATENT OFFICE.

SOLOMON CHARLES GINS, OF CHARLEROI, PENNSYLVANIA.

FLYING MACHINE.

Application filed June 2, 1926. Serial No. 113,251.

This invention relates to flying machines and has for an object the provision of a flying machine which is constructed so as to split the air and therefore form a minimum 5 amount of resistance.

Another object of the invention is the provision of novel soaring and gliding means, so as to provide control and permit a safe landing in the event of mishap or 10 trouble with the motor.

A further object of the invention is the provision of means included in the gliding means whereby the latter may be controlled to provide a brake.

15 With the above and other objects in view, the invention further includes the following novel features and details of construction, to be hereinafter more fully described, illustrated in the accompanying drawings and 20 pointed out in the appended claims.

In the drawings:

Figure 1 is a front elevation of an airplane constructed in accordance with the invention.

25 Figure 2 is a side view of the same.

Figure 3 is a top plan view.

Figure 4 is a detail perspective view of one of the side tubes.

30 Figure 5 is a similar view of the upper tube.

Referring to the drawings in detail wherein like characters of reference denote corresponding parts, the reference character 10 indicates the body or fuselage of the machine, the rear end of which carries oppositely extending vertical rudders 11 and a vertically extending horizontal rudder 12, suitable means being provided for controlling these rudders. At the forward end of 35 the fuselage there is provided a hood 13 which may house a motor, the hood and fuselage being provided with ventilators 14, as shown in Figure 2 of the drawings.

40 Extending downwardly from the fuselage 45 are struts or ribs 15 which are braced as indicated at 16 and which carry at their lower ends, an axle 17. Wheels 18 are mounted upon the outer ends of the axle and provide the usual landing gear. Extending from opposite sides of the fuselage are wings 19 and connecting these wings with the struts or ribs 15, are braces 20.

Supported by the structure just described are tubes 21 and 22. The tubes 21 extend longitudinally upon opposite sides of the fuselage and have extending laterally there-

from horizontally disposed vanes or wings 23, while extending from the front and rear end portions of the tubes 21 are longitudinally disposed downwardly and upwardly 60 extending wings or vanes 24 and 25. These vanes 24 and 25 act to split the wind and offer a minimum amount of resistance. The vanes 24 and 25 are shaped as shown in Figure 4 of the drawings and are hollow, 65 their open end being disposed toward the rear of the airplane. When the plane is travelling through the air, a vacuum is thus provided within these wings which acts to increase the buoyancy of the machine. The 70 forward portion of the fuselage or hood 13 is provided with a similar vane 26.

The tube 22 is provided with laterally and upwardly extending vanes 27 which extend longitudinally of the tube and are 75 shaped as shown in Figures 2 and 5 of the drawings.

The tubes 21 and 22 are open throughout their lengths so that the air may pass freely therethrough but the passage of air may be controlled by valves or dampers 28 and 29 located respectively at the forward and rear ends of the tubes. These valves are pivotally mounted as shown at 30 and are normally held in closed position by springs 31. 80 Connected with the rear valves 29 are cables 32 which are in turn connected to an operating lever 33 located within the fuselage. The valves 28 are connected by cables 34 with a lever 35 so that by operating the 85 levers 33 and 35, the valves 29 and 28 may be adjusted to regulate the passage of air through the tubes. The tubes are provided with rearwardly extending overhanging portions 36.

90 In use, the valves 28 and 29 may be fully opened so as to permit the free passage of air therethrough, or the valves may be adjusted to regulate the amount of air passing through the tubes. The forward speed of the airplane may thus be regulated. In addition, the front valves 28 may be opened and the rear valves closed so that the latter will act as a brake. Further, the rear valves may be opened and the forward valves 95 closed, whereupon a partial vacuum will be provided in the tubes and the buoyancy of the machine will be increased.

100 The machine is provided with a propeller 36' having an auger-like formation. This 110 propeller may be driven by a motor of any suitable type.

While the invention is illustrated and described in connection with an airplane, it is equally well adapted for use in connection with dirigibles or like lighter than air machines and it is therefore not the purpose of the present application to limit the application of the invention in this respect. 5

The invention is susceptible of various changes in its form, proportions and minor 10 details of construction and the right is herein reserved to make such changes as properly fall within the scope of the appended claims.

Having described the invention what is 15 claimed is:—

1. In an airplane, a fuselage, wings extending therefrom, tubular members carried by and extending longitudinally of the fuselage, rearwardly extending overhanging portions projecting from the upper portions of 20 the rear ends of the tubular members, and means to control the passage of air through the tubes.
2. In an airplane, a fuselage, wings extending therefrom, tubular members carried 25

by and extending longitudinally of the fuselage, valves at opposite ends of the tubes to control the passage of air therethrough and means to simultaneously control all of the valves at the forward ends of the tubes and means to simultaneously control all of the valves at the rear ends of the tubes. 30

3. In an airplane, a fuselage, wings extending therefrom, tubular members carried by and extending longitudinally of the fuselage, means to control the passage of air through the tubes and relatively short upper and lower longitudinally disposed wedge-shaped fins located at the front and rear ends of the tubes. 35

4. In an airplane, a fuselage, wings extending therefrom, tubular members carried by and extending longitudinally of the fuselage, means to control the passage of air through the tubes and longitudinally disposed hollow wedge-shaped fins open at their rear ends and extending from the tubes. 40 45

In testimony whereof I affix my signature.

SOLOMON CHARLES GINS.
